(57) **CLAIM**

I claim the ornamental design for a teeth whitening headset, as shown and described.

DESCRIPTION

FIG. 1 is a front perspective view of a teeth whitening headset showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front perspective view thereof. The broken lines showing a portion of the human form is included for illustrating environmental structure and form no part of the claimed. The connecting hose for the teeth whitening headset shown in the figures broken in the middle for ease of illustration.

A headset having a battery housing attached via a flexible power cord to a light emitting mouthpiece for whitening teeth.
